UNITED STATES PATENT OFFICE

BARTHOLOMEW J. MORRISON, OF BALTIMORE, MARYLAND, ASSIGNOR TO THE COALE MUFFLER & SAFETY COMPANY, OF BALTIMORE, MARYLAND, A CORPORATION OF MARYLAND

BLOWER VALVE

Application filed November 26, 1929. Serial No. 409,817.

The blower valve, which is the subject of the invention, is variously applied, being used in locomotives for discharging steam into the stack to create a forced draft wherever forced draft is required, shutting off the flow of steam when, for any reason, the natural draft is sufficient. These valves are also used to control the steam supply in blowing out boiler tubes and under various circumstances where immediate control of a supply of steam which can be instantaneously released to flow at high speed, is desired. With the blower valves formerly in use, a considerable amount of difficulty has been encountered due to the tendency to lose the balances or upper and lower valve seats.

This difficulty incident to the loss of such valve parts, occurs mainly when the pipe connections are removed for any reason as when locomotives are dismantled for repairs, the different parts being removed by different gangs of steamfitters, boiler workers, valve men and the like. When the blower valves as formerly constructed are thus removed, there is nothing to hold the valve discs, otherwise known as the valve seats, in position, so that both discs or seats drop out and are lost. When it becomes necessary to reassemble the locomotive or other installation containing such valves, these parts are missing and are replaced in various ways, either by obtaining new ones from the valve manufacturer, or, on account of the tendency of railway shops to make whatever is required in the way of repairs, they are replaced by discs or seats made in the shop. Such replacements cause great difficulty, delay and expense. To overcome this difficulty is the object of the invention.

With the foregoing facts in view, the present invention provides a blow off valve provided with means for securing the lower seat or disc, as it may be termed, in position, so that neither seat or the disc can be accidentally released. It will be understood in this connection that the upper valve disc or seat rests on the lower one and is removably connected to the valve stem to be rotated thereby. The lower seat holds the upper one in operative position. The securing

means which is the subject of the invention permits free play of the lower disc relatively to the casing so that the lower disc may be positioned by suitably formed surfaces provided for this purpose on the valve casing and the adjacent coupling.

In the accompanying drawings I have illustrated a blower valve for the various uses described embodying the features of my invention in the preferred form.

In the drawings:

Figure 1 is a section in a plane including the axis of the valve stem or spindle.

Figure 2 is a section in a plane at right angles to the plane of Figure 1 and including the line 2-2 of Figure 1, looking downwardly.

Figure 3 is a section on the line 3-3 looking upwardly.

Figure 4 is an elevation of the upper valve disc, also referred to as the upper valve seat, a portion to be broken away to show the internal formation of the disc in section.

Figure 5 is a corresponding view of the lower valve seat or disc.

Figure 6 is a side elevation of the valve casing, the lower portion being broken away, exposing the valve disc and seat. This view also shows the valve coupling member in a position slightly removed in the direction of the axis from its operative position in connection with the valve.

Figure 7 is a plan view taken from a position indicated by line 7-7, looking upwardly at the valve casing and seats with the coupling member removed.

Referring to the drawings by numerals, each of which is used to indicate the same or similar parts in the different views, the construction shown comprises a valve casing 1, containing upper valve disc or seat 2 and lower valve disc or seat 3. The lower valve seat 3 is shown as having a peripheral flange 4 projecting outwardly from its lower edge. This flange projects beneath the bottom edge 5 of the valve casing and in the assembled relation of the valve parts it is held between the bottom edge of the valve casing and the inner horizontal surface 6 of the coupling member 7, being suitably packed at 6'. 100

The surfaces 5 and 6 are suitably formed and located to position the lower valve disc at right angles to the spindle. The valve casing and coupling member are held in the assembled relation by means of intermeshing threads 8 formed on the inner vertical surface of the coupling member 7 and on the outer surface of the casing 1.

The valve casing is shown as formed with 10 a central vertical opening 9 in its top wall 10, which opening 9 serves as a bearing for the valve stem or spindle 11, which projects downwardly through this opening, being shouldered at 12 to position the stem 11 and flattened in a vertical plane at 14 below the shoulder forming a screw driver like portion at the lower end of the stem, which engages a slot 15 formed for this purpose on or in the upper surface of a valve disc 2. The 20 leakage of steam around the valve stem is prevented by means of a gland or packing 13 of the usual type, the details of which are not material to the invention.

To provide for the opening of the valves 25 the disc 2 and the valve seat 3 are formed with similarly placed vertically disposed openings 17 and 18, which are thrown into registration in open position of the valve and out of registration in the closed position. 30 The upper disc or valve seat 2 is further held in close contact with the lower disc or seat 3 to prevent leakage between said discs when the valve is closed, this result being accomplished by means of a coil spring 19 enclosed 35 in a suitable vertical axial opening or socket 19' in the spindle, said spring bearing at one end against the upper end of said opening and at the other end against the disc 2. The spring is shown as contacting the bottom 40 of slot 15 in the disc.

40 The coupling member 7 is connected to steam pipe 20, leading a supply of steam under pressure from a suitable source. In the form of the invention shown, the coupling member 17 is provided for this purpose with a tapered threaded opening 21 in which the upper threaded end of the pipe 20 is engaged by means of a corresponding thread 22 on the pipe.

50 An important feature of the invention resides in the provision of a suitable loss preventing connection between the lower valve disc or valve seat member 3 and the valve casing, which connection prevents the escape 55 and loss of the valve seats or discs 2 and 3, when the valve is disconnected.

In the form of the invention shown the loss preventing means connecting the valve seat or lower valve disc 3 to the valve casing 60 consists of a bayonet slot or slots 24 in the casing, said slots each having a downwardly disposed opening 25 through the bottom edge 5 of the casing and a horizontal portion or seat 26. This slot cooperates with and receives a projecting member 27 on the valve

seat 3, see particularly Figure 5, which may be referred to as a projecting pin or dog engaging the bayonet slot. In the form shown there is, in fact, a slot 24 on each side of the casing, and a pin or dog 27 on each side of the seat or disc 3. In the form shown the bottom of the lower valve seat 3 is chambered at 28 to facilitate the flow.

When the locomotive is overhauled or, for 70 any reason, the pipes in which the valve is located are removed or dismantled, the valve would ordinarily be disconnected from the pipes by removing the coupling 7, but the valve and casing may be subject to considerable rough treatment without loss of the valve 75 seat or discs.

80 In this way the difficulty and inconvenience, loss and delay, incident to replacing the discs in various ways either by the purchase of new ones from the manufacturer or by the expedient of making new ones in the shop, is overcome and the practical efficiency of the valve is greatly increased, a point having an 85 important bearing on the situation being that the valve discs or seats when once worn in are 90 more satisfactory in practice than any new ones which can be substituted, and only those which are produced with the utmost care and skill resulting from experience in this particular line and special equipment for this 95 purpose are practically operative. For this reason satisfactory replacement is always difficult and frequently impracticable or nearly so.

I have thus described specifically and in 100 detail a blower valve embodying the features of my invention in the preferred form in order that the manner of constructing, using and applying the same may be fully understood, however, the specific terms herein are 105 used descriptively rather than in a limiting sense, the scope of the invention being defined in the claims.

110 What I claim as new and desire to secure by Letters Patent is:

1. The combination in a blower valve substantially as described of a valve casing, a lower perforated disc, an upper perforated disc free to rotate relatively thereto, a spindle 115 separate from the discs and having means for engaging the upper disc to rotate it, a coupling member having a threaded engagement with the bottom of the casing, the lower disc having means for holding the same against rotation, means for securing said bottom disc in said casing said means permitting free play of the disc relatively to the casing, and positioning means for the lower disc, said securing means serving to prevent the loss of the discs when the coupling is removed from 120 the valve casing.

2. The combination in a blower valve substantially as described of a valve casing, a lower perforated disc, an upper perforated disc free to rotate relatively thereto, a spindle 125

separate from the discs and having means for engaging the upper disc to rotate it, a coupling member having a threaded engagement with the bottom of the casing, said lower disc being
5 adapted to be secured between said casing and said coupling member, and a bayonet slot connection for securing said bottom disc in said casing to prevent the loss of the discs when the coupling is removed from the valve cas-
10 ing.

3. The combination in a blower valve substantially as described of a valve casing, of a lower perforated seat, an upper perforated seat, free to rotate relatively to the lower seat, a spindle separate from the seat and having means for engaging the upper seat to rotate it, a coupling member having a threaded engagement with the bottom of the casing, the lower seat having means for holding the same
15 in position, said means being adapted to be secured between said casing and said coupling member and means for securing said bottom disc in said casing, said securing means permitting free play of the disc relative to
20 the casing so that it may be positioned between the casing and the coupling member and serving to prevent the loss of the discs when the coupling is removed from the valve casing.

CERTIFICATE OF CORRECTION.

Patent No. 1,794,791.

Granted March 3, 1931, to

BARTHOLOMEW J. MORRISON.

It is hereby certified that the assignee in the above numbered patent was erroneously described and specified as "The Coale Muffler & Safety Company, of Baltimore, Maryland, a corporation of Maryland", whereas said assignee should have been described and specified as The Coale Muffler & Safety Valve Company, of Baltimore, Maryland, a corporation of Maryland, as shown by the records of assignments in this office; and that the said Letters Patent should be read with this correction therein that the same may conform to the record of the case in the Patent Office.

Signed and sealed this 14th day of April, A. D. 1931.

(Seal)

**M. J. Moore,
Acting Commissioner of Patents.**
